corporation of Michigan

Filed June 30, 1969, Ser. No. 17,946

Term of patent 14 years

Int. Cl. D8—03

U.S. Cl. D8—171

FIG. 2.

FIG. 1.

FIG. 3.

FIG. 4.

FIG. 5.

FIG. 6.

FIG. 1 is a perspective view of the range handle;
FIG. 2 is a front elevational view thereof;
FIG. 3 is a side elevational view thereof;

FIG. 4 is a cross sectional view through lines IV—IV of FIG. 2;

FIG. 5 is a perspective view, like FIG. 1, of a modified form of the range handle; and

FIG. 6 is a side elevational view of another range handle, having a similar FIG. 4 cross section.

In FIGS. 1, 2, and 5, only one-half of the handle has been shown, the other half being symmetrical about the transverse centerline thereof.

I claim:

The ornamental design for a range handle, as shown and described.
